UNITED STATES PATENT OFFICE.

OTIS A. MYGATT, OF NEW YORK, N. Y.

DESIGN FOR A PRISMATIC-GLASS REFLECTOR.

No. 37,983.

Specification for Design.

Patented May 1, 1906.

Application filed July 31, 1905. Serial No. 272,132. Term of patent 14 years.

To all whom it may concern:

Be it known that I, OTIS A. MYGATT, a citizen of the United States, residing at New York, in the county of New York and State of New York, have invented a certain new, original, and ornamental Design for Prismatic-Glass Reflectors, of which the following is a specification, reference being had therein to the accompanying drawings, forming part thereof.

Figure 1 is a side elevation of a reflector embodying my design. Fig. 2 is a perspective view from a plane or point somewhat below the reflector.

The reflector is composed of transparent glass of the form shown. Below the top collar the body is externally covered with reflecting-prisms, as indicated in full lines in Fig. 1. These prisms show through the glass, as attempted to be indicated in dotted lines, Fig. 2.

I claim—

The ornamental design for prismatic-glass reflector, as shown and described.

OTIS A. MYGATT.
